(57) **CLAIM**

The ornamental design for an awning, as shown and described.

DESCRIPTION

FIG. 1 is a top view of an awning, showing my new design; FIG. 2 is a bottom view thereof;

FIG. 3 is a front view thereof;

FIG. 4 is a back view thereof;

FIG. 5 is an enlarged left side lateral view thereof;

FIG. 6 is an enlarged right side lateral view thereof; and,

FIG. 7 is a perspective view thereof.

The broken lines in the figures depict portions of the awning that form no part of the claimed design. The small tick marks in the gaps in FIGS. 5 and 6 form no part of the claimed design.
